UNITED STATES PATENT OFFICE

169,361

PORTABLE POWER-OPERATED SAW

Edmund C. Dudek, Evergreen Park, Ill., assignor
to Portable Electric Tools, Inc., Chicago, Ill., a
corporation of Illinois

Application December 11, 1952, Serial No. 22,647

Term of patent 14 years

(Cl. D93—3)

To all whom it may concern:

Be it known that I, Edmund C. Dudek, a citizen of the United States, residing at Evergreen Park, in the county of Cook and State of Illinois, have invented a new, original, and ornamental Design for a Portable Power-Operated Saw, of which the following is a specification, reference being made to the accompanying drawings forming a part hereof.

In the drawings:

Fig. 1 is a front perspective view of a portable power operated saw showing my new design;

Fig. 2 is a front elevational view;

Fig. 3 is a plan view;

Fig. 4 is a side elevational view taken from the left in Fig. 2;

Fig. 5 is a side elevational view taken from the right in Fig. 2; and

Fig. 6 is a rear view.

The dominant features of my design reside in the portions shown in full lines.

I claim:

The ornamental design for a portable power-operated saw, substantially as shown and described.

EDMUND C. DUDEK.
